UNITED STATES PATENT OFFICE.

JOHN J. RUDDICK, OF NEWTON, MASSACHUSETTS, ASSIGNOR TO UNITED STATES ELECTRIC SIGNAL COMPANY, OF PORTLAND, MAINE.

SIGNAL SYSTEM.

No. 903,785.

Specification of Letters Patent.

Patented Nov. 10, 1908.

Application filed May 23, 1908. Serial No. 434,666.

To all whom it may concern:

Be it known that I, JOHN J. RUDDICK, a citizen of the United States, residing at Newton, county of Middlesex, and State of 5 Massachusetts, have invented an Improvement in Signal Systems, of which the following description, in connection with the accompanying drawing, is a specification, like letters on the drawing representing like 10 parts.

This invention relates to electric block signal systems which are especially adapted for use in connection with railways for indicating to a train or car whether or not the 15 block ahead is free or occupied.

The invention has been herein shown as applied to an electric railway, but it is 20 equally applicable to steam railways.

The principal object of the invention is 25 to provide a signaling system which will not be liable to be disabled by lightning, crossed wires, or similar causes. In order to secure this end I have provided a signal system in which the wire or wires which connect the 30 two signal boxes at opposite ends of a block are normally disconnected from the ground so that under normal conditions there is no ground connection at either box which could afford a possible path for a lightning charge. 35 The result is that a stroke of lightning will select some object such as a tree which affords a better path to earth than the wire or wires connecting the signal boxes and forming part of the signaling circuit.

In the preferred form of my invention 40 there are two wires extending the length of the block and connecting the boxes at opposite ends thereof. One of these wires constitutes part of the signal circuit and the 45 other constitutes part of the signal-restoring circuit. Under normal conditions when the signals on the block are set at "safety", the two wires are electrically connected at each end and are each disconnected from both the 50 feed and the ground, whereby a closed metallic loop or circuit is established between the signal boxes which has no connection with either the feed or the ground. With such an arrangement there will be no tendency 55 for the lightning to strike either of the wires when the signal is at safety because of the lack of ground connection.

To guard against setting the signal by any 60 accidental crossing of the two wires, I place 55 the signal in a signal-containing circuit

which is normally disconnected from said closed loop so that even if the wires of the loop become crossed the circuit containing the signal is not affected.

In the embodiment of the invention herein 60 illustrated the signal is set at "danger" by opening the normally closed loop or circuit and connecting it at one place with the feed and at another place with the ground and also connecting it with the signal whereby 65 a complete circuit is established from the feed to the ground which includes the signal. This is preferably done automatically by the car or train as it enters a block. The 70 signal is restored to safety by disconnecting the loop from the feed and from the ground and again closing said loop.

In the drawings wherein I have illustrated 75 one embodiment of my invention, Figure 1 is a diagrammatic view showing a block of a 80 railway track with a signal box at each end thereof, the parts being shown in said view in their normal condition; Fig. 2 is a simplified diagrammatic view of the closed metallic circuit connecting the two signal boxes at 85 opposite ends of the blocks; Fig. 3 is a diagrammatic view showing the boxes at the adjacent ends of two adjacent blocks; Fig. 4 is a diagrammatic view of the box at the entering end of the block showing the circuit 90 which is first made when the car enters the block; Fig. 5 is a diagrammatic view of the two boxes at opposite ends of the block showing the second path of the circuit during the 95 setting operation of the signal; Fig. 6 is a simplified diagrammatic view of the circuit shown in Fig. 5; Fig. 7 is a diagrammatic view of the boxes showing the circuits when the signals have been set by a car entering the block; Fig. 8 is a simplified diagrammatic 100 view of the circuit shown in Fig. 7; Fig. 9 is a diagrammatic view of the signal box at the exit end of the block showing the first course of the circuits; Fig. 10 is a diagrammatic view of the same box showing the course of the restoring circuit; Fig. 11 is a plan view 105 of the magnets and their armatures located in either of the boxes; Fig. 12 is a section on substantially the line $x-x$, Fig. 11, looking toward the top of the sheet; Fig. 13 is a view on the same line $x-x$, looking toward the bottom of the sheet; Fig. 14 is a section on the line $y-y$, Fig. 11; Fig. 15 is a detail of the armatures for the magnets d, e and f .

In the drawings I have shown the block 110

on the track which is protected by the signal as including a space of single track between the two turn-outs 3 and 3^a. The signal system includes a signal box at each end of the 5 block, said signal boxes being designated generally by A and B. Under normal conditions the two signal boxes are connected in a closed metallic circuit or loop, as shown in the simplified diagrammatic view in Fig. 2, 10 said circuit comprising the two wires 4 and 5 (4 being a signal circuit wire and 5 being a signal-restoring circuit wire) which are disconnected from the feed wire 6 or other source of electricity, and also from the 15 ground or return circuit which may be the rails 7 of the track. When the car enters the block at signal box A the closed loop is opened at signal box A and connection is made at the open ends thereof with both the 20 feed and the ground whereby a signal-setting circuit is established such as shown in the simplified diagrammatic view in Fig. 6, and which extends from the feed 6 to the signal box A, thence through wire 4 to the signal box B, thence back to signal box A through wire 5 and thence to the ground. In traversing this circuit the current passes through both signal boxes and thus operates to set the signal at each end of the block. 25 After the signals have been set this signal-setting circuit is discontinued and a signal circuit for maintaining the signals in operation is established, such as shown in the simplified diagrammatic view Fig. 8, the current 30 being taken from the feed 6 to signal box A, from the latter through the signal wire 4 to signal box B and thence to the ground or return wire 7. When the car passes out from the block the signal is restored by establishing a signal-restoring circuit through 35 both signal boxes by means of the signal-restoring wire 5. These results are secured in the present embodiment by a signal box mechanism which comprises two signal-setting magnets *a*, *b*, a lock-releasing magnet *c*, a signal-restoring magnet *f*, and two current-directing magnets *d* and *e*. These magnets may conveniently be arranged in the manner shown best perhaps in Figs. 11 to 15, although a similar arrangement is shown diagrammatically in the other figures of the 40 drawings.

The signal-setting magnets *a* and *b* have situated between them a swinging armature 45 9 which is adapted to be attracted toward the poles 10 of either magnet as it is energized. This swinging armature is mounted on a suitably-journalized rock-shaft 11 and it carries a head 12 of insulating material carrying the two pairs of insulated contacts 13, 14 and 15, 16.

17, 18 are a pair of insulated contacts which are adapted to be bridged by the contact 13 when the armature 9 is attracted by 60 the energized magnet *b*, and 19, 20 are a

similar pair of contacts adapted to be bridged by the contact 15 when the armature 9 is thus attracted.

21, 22 and 23, 24 are two pairs of insulated contacts adapted to be bridged by the contacts 14 and 16 respectively when the armature is attracted by the energized magnet *a*.

The armature 9 is normally held in its neutral position between the two magnets, 75 as shown in Fig. 11, by a retaining device herein shown as an arm 26 pivoted at 27 to a suitable support and having a roll or projection 28 which engages in a V-shaped recess 29 formed in an arm 30 rigid with the 80 rock-shaft 11. The arm 26 carries at its end a contact 31 which is suitably insulated from the arm, as at 32, said contact 31 normally bridging two suitably-supported insulated contacts 33, 34. When the armature 85 9 is swung in either direction by either of the magnets *a*, *b*, the sides of the V-shaped notch 29 by acting on the roll 28 force the retaining device 26 backwardly thereby disengaging the contact 31 from the contacts 90 33, 34.

The rock-shaft 11 has rigid therewith an arm 35 which co-operates with a lock 36 to lock said rock-shaft in the position it assumes when attracted by either of the magnets *a* or *b*. While this lock may have any suitable construction I have herein shown it as comprising a head 37 carried by the arm 35 and against which rests the locking projection 36, the latter being sustained by an 100 arm 38 suitably pivoted at 39. When the armature 9 is attracted by either of the magnets *a* or *b*, the turning of the rock-shaft 11 carries the head 37 beyond the projection 36 thereby allowing said projection to drop 105 down back of the end of the head and preventing the shaft 11 from returning to its normal position. The arm 38 may be acted on by a suitable spring which will normally tend to force it into this locking position, 110 or the signal box may be so placed that the arm will be thrown into this locking position by gravity. Said arm has a portion *c'* thereof which acts as an armature for the lock-releasing magnet *c*.

The magnets *d*, *e* and *f* each have swinging armatures designated, respectively, *d'*, *e'*, *f'*. These armatures are independently pivoted in suitable bearings as at 46, as shown best in Figs. 13 and 15. The armature *d'* carries two contacts 47 and 48 which are insulated from each other, the contact 47 being adapted to engage two insulated contacts 49 and 50 when the armature is attracted by the magnet *d*, and the contact 48 being adapted to bridge two insulated contacts 51 and 52 when the armature is in its normal position, as shown in Fig. 11. The armature *e'* has connected therewith an insulated contact 53 adapted to bridge two 130

insulated contacts 54 and 55 when the armature is attracted by the magnet *e*, and the armature *f*' has associated therewith an insulated contact 56 adapted to bridge two insulated contacts 57, 58 when the armature is in its normal neutral position. The armatures *d*' and *e*' are provided with means so that whenever either is attracted by its magnet the other is locked against movement, this being conveniently accomplished by providing each armature with the lateral projection 60 which coöperates with a locking nose 61 carried by a rock-shaft 62.

The rock-shaft has extending therefrom two arms 63, each of which is adapted to be engaged by a pin 64 extending from the armature.

The locking projections 61 have such a shape relative to the noses of the projections 60 that when either armature is attracted towards its magnet the rock-shaft will be turned by engagement of one of the pins 64 with the arm 63 thereby swinging one of the projections 61 down in front of the nose of the magnet which remains in neutral position, said noses being so shaped that when either armature is attracted the corresponding nose will pass under the projection 61 before it strikes the arm 63.

I have above briefly described the mechanical construction of the armatures and the magnets of each signal box, and I will now describe the manner of wiring each box, and since the manner of wiring the two boxes at each end of the block is alike, a description of one will suffice for both.

The feed wire 6 or other source of electricity is connected by a wire 70, which preferably connects with a white signal lamp 71, and a wire 72 with the coils of the signal-setting magnet *a*. The coils of said magnet are connected by a wire 73 with the contact 21. Said contact 21 is connected by a wire 74 which preferably has suitable resistance 75 therein with the coils of the magnet *d*, and said magnet *d* is connected by a wire 76 to a suitable track switch 77 adapted to be operated to close the circuit by the car passing over the track and which is herein shown as arranged to connect the wire 76 with the ground or return wire. The wire 70 is also connected by a wire 78 with the coils of the magnet *e*, and said magnet is connected by a wire 79 with another track switch 80. The two magnets *d* and *e* and their circuits are merely for the purpose of properly directing the current when the car enters or leaves the block, all as will be more fully described, and are necessary because the connection with the ground is established by means of track switches which are operated by the wheels of cars passing over the track. If the circuits were closed by trolley switches, that is, switches adapted to be closed by the trolley the two magnets as

herein shown would not be necessary because the current would be given its proper direction by the trolley switch. These track switches may have any suitable construction. In my co-pending application Serial No. 70 434,665 filed May 23, 1908, I have shown a track switch suitable for use in the device herein illustrated.

The contact 22 is connected by a wire 81 with the contact 57, and the contact 58 is 75 connected to the signal wire 4. The signal-restoring wire 5 is connected to each of the contacts 51, 49 and 54. The contact 52 is connected by wire 82 to the coils of the lock-releasing magnet *c* and the coils of said magnet are connected by wires 83 and 84 to the two contacts 19 and 23. The contacts 20 and 24 are connected by wires 85 to the wire 72. The coils of the lock-releasing magnet are also connected by wires 83 and 86 with 80 the contact 33 and the contact 34 is connected by a wire 870 with the coils of the setting magnet *b*. The other end of the coil of setting magnet *b* is connected by a wire 87 with the wire 81 and said magnet is also 90 connected by the wire 88 with the contact 17. The contact 18 is connected by a wire 89 to the return circuit 7 and said wire 89 has a red signal light 90 therein. The wire 89 is also connected by a wire 91 with the contact 95 50. The wires 89 and 70 constitute what I have called the signal containing circuits.

As stated above, under normal conditions the two signal boxes A and B are connected by a metallic circuit and are disconnected 100 both from the ground and from the feed wire 6, as shown both in the simplified diagram Fig. 2 and in the complete diagram Fig. 1. In Fig. 1 the heavy line indicates this closed metallic circuit which is formed 105 by the contacts when the armatures are in their neutral position. This circuit includes the signal-restoring wire 4, contacts 58, 56, 57, wire 81, 87, coils of signal-setting magnet *b*, wire 870, contacts 34, 31, 33, wire 110 86, coils of the lock-releasing magnet *c*, wire 82, contacts 52, 48, 51, and signal wire 5, and thence through the other box in exactly the same way except reversed, as clearly shown in Fig. 1. 115

When a car enters the block a preliminary signal-setting circuit is established through signal-box A in the manner shown in heavy lines in Fig. 4 by the closing of the switch 77, for as soon as said switch is closed, there 120 is a clear circuit from the feed 6 through wire 70, 72, signal-setting magnet *a*, wire 73, contact 21, wire 74, magnet *d* and wire 76, as shown in heavy lines in Fig. 4. This results in opening the closed loop at signal 125 box A and connecting the signal wire 4 with the feed 6 and the signal-restoring wire 5 with the ground, as shown in the simplified diagram Fig. 6, so that a signal-setting circuit is established which passes through both 130

signal boxes. The current in said circuit operates mechanism which sets the signals at both ends of the block.

The detail manner in which the signal-setting circuit is established is as follows: When this circuit is completed even momentarily, the magnet *d* is energized thereby attracting the armature *d'* and breaking the connection between the contacts 51, 52, and making the connection between the contacts 49, 50. Simultaneously the signal-setting magnet *a* is energized thereby attracting the armature 9 whereby the contacts 21, 22 and 23, 24 are bridged and simultaneously the arm 26 is swung backwardly by the walls of the V-shaped notch 29 thereby breaking the connection between the contacts 33, 34. As soon as the signal-setting magnet *a* has been energized thereby to attract the armature 9, said armature becomes locked in this position by the automatically-acting lock 36 as above described. The bridging of the contacts 21, 22 and 23, 24 by the energization of the magnet *a* operates to establish a final signal-setting circuit which leads through signal box B so that the mechanism at said box is set in operation to set the signal at the far end of the block. This final signal-setting circuit is shown in the simplified diagram view Fig. 6.

The circuit in detail is shown in the heavy lines Fig. 5 and is as follows: From the feed wire through wires 70, 72 to the magnet *a*, thence through wire 73 to contact 21, thence to contact 22 and through wire 81 to contact 57, from contact 58 to the signal wire 4 and to the contact 58 of box B, through contacts 56, 57, wires 81, 87, signal-setting magnet *b* of box B, wire 870, contacts 34, 31, 33, wires 86, 83, coils of the lock-releasing magnet *c*, wire 82, contacts 52, 48, 51, signal-restoring wire 5, thence to contacts 49, 47, 50, and wire 91 to the ground 7. When the current is thus established the signal-setting magnet *b* at box B is energized, and the armature 9 at said box is therefore drawn over by said magnet and locked in such position and the contacts 17 and 18 and 19 and 20 are bridged. This movement of the armature 9 and the contacts carried thereby breaks the electric connection between the signal-restoring wire 5 and the signal wire 4 at signal box B and connects said signal wire 4 to the ground and to the signal at said signal box, and thus completes the signal circuit and sets the signals.

The complete signal circuit is shown in the simplified diagram Fig. 8, and is also shown in heavy lines in Fig. 7. The first part of this circuit from signal box A to signal box B is exactly as shown in Fig. 5, and as above described the energizing of the signal-setting magnet *b* at box B results in breaking the connections between the contacts 33, 34 (thus disconnecting the signal-

restoring circuit 5 from the signal circuit 4) and establishing connections between the contacts 17, 18 so that the current after passing through the magnet *b* takes the wire 88, contact 17, 13, 18 and wire 89 to the ground. 70 The wire 89 has the red light in it and constitutes a signal-containing circuit, and the operation of the signal-setting magnet *b* connects the signal-containing circuit with the signal circuit and then sets the danger 75 signal at the exit end of the block. The wire 70 which also constitutes a signal-containing circuit at the entering end of the block, has already been connected to the signal circuit, and when said circuit is complete a 80 white light is exhibited at the entering end of the block and a red light at the opposite end of the block. This condition will continue until the car leaves the block. When the car does thus leave the block, the signal 85 system is restored to the condition shown in Figs. 1 and 2 in which the signal circuit wire 4 and the signal-restoring wire 5 are both disconnected from the signal and are connected at their ends to form the closed 90 loop. This restoring of the signal to the normal condition is secured by completing a circuit through the signal-restoring wire and through both of the lock-releasing magnets *c* whereby said magnets become energized and thus operate to release the locks 95 36 whereby the armatures 9 are returned to their neutral position, as seen in Fig. 1, the returning of the armatures to this neutral position operating to restore the circuits to 100 the condition shown in Fig. 1. The first step in restoring the signal occurs when the car leaving the block operates the track switch 80 at the exit end of the block. The closing of this switch establishes a preliminary signal-restoring circuit such as shown in Fig. 9 which includes the wires 70, 78, magnet *c*, wire 79, and switch 80. When this circuit is closed the magnet *c* becomes energized and its armature *c'* is attracted 110 whereby the contact 53 is caused to bridge the contacts 54, 55. When the car passes onto the siding 3^a it operates the track switch 103 at the siding which is connected with the magnet *f* by a wire 104, and the operation of this track switch results in closing the signal-restoring circuit through the signal-restoring wire 5 and the two lock-releasing magnets *c* in the manner shown in heavy 115 lines in Fig. 10. The complete signal-restoring circuit thus formed is connected with the feed at two places, one branch of said circuit passing through each of the magnets *c*. The circuit which extends through the lock-releasing magnet *c* at the 120 signal box B comprises the wires 70, 72 and 85, contacts 20, 19, wire 83, the coils of the lock-releasing magnet *c*, wire 82, contacts 52, 51, and the signal wire 5, contacts 54, 53, 55, wire 105, magnet *f*, wire 104, and switch 103. 125 130

The circuit through the lock-releasing magnet *c* at signal box A comprises the wire 70, 72, 85, contacts 24, 23, wire 84, lock-releasing magnet *c*, wire 82, contacts 52, 51, 5 and signal-restoring wire 5, contacts 54, 55 at signal box B, magnet *f* and wire 104. The two lock-releasing magnets *c* are thus in parallel and the current taken from the feed at two places passes through both of them, energizes them, and thus causes the locks 36 at each signal box to be released from the heads 37, thereby permitting the armatures 9 both to return to their neutral position. The movement of said armatures 15 into their neutral or central position breaks the connection between the signal circuit 4 and the feed at signal box A and also breaks the connection between said signal circuit and the ground at signal box B. As soon as 20 the armatures 9 return to their normal position the contact 31 is again brought into engagement with the contacts 33, 34 at each signal box and the circuits 4 and 5 are thereby connected together at their ends again, 25 thus restoring the system to the condition shown in Figs. 1 and 2.

With the embodiment herein shown it is necessary that the contact 53 should remain bridging the contacts 54, 55 while the car is 30 passing from the track switch 80 to the track switch 103 on the siding and therefore I have provided an automatic locking device for holding the armature *e'* in the position in which it is attracted by the magnet *e*. This 35 locking device is shown in Figs. 11 to 15, and comprises a pin 100 extending laterally from the armature *e'* and a pivoted locking pawl 101 which is adapted to engage automatically with the locking pin 100, as shown 40 in dotted lines Fig. 14, when the armature *e'* is attracted. This locking pawl acts to retain the armature *e'* in its position with the contact 53 bridging the contacts 54, 55 until said pawl is released when the magnet *f* is 45 energized. The armature *f'* of the magnet *f* has extending therefrom a projection 106 which is adapted to engage an arm 107 rigid with the pawl 101 thereby to release said pawl from the pin 100 and permit the armature *e'* to resume its normal position under 50 the influence of a spring or other suitable mechanism. When the magnet *f* is energized the attraction of its armature breaks the signal circuit between the contacts 57, 58, 55 and as stated above, the movement of the armatures 9 into their normal position operates to connect the two ends of the wires 4 and 5, thus forming the closed loop above described. 60 It will be noted that at the entering end of the block the track switch 77 is slightly in advance of the track switch 80 so that the switch 77 will be operated first. It is the switch 77 at the entering end of the block 65 that is utilized for establishing the prelimi-

nary signal-setting circuit, and the switch 80 at the exit end of the block is used for setting the preliminary signal-restoring circuit.

The interlocking connection between the armatures *d'* and *e'* is for the purpose of 70 preventing the armature *e'* from being operated when the car passes over the switch 80 at the entering end of the block so that when the car enters the block the proper circuit will always be established for setting 75 the signal.

At the leaving end of the block the track switch 80 is first operated thereby to set the preliminary signal-restoring circuit and when the armature *e'* is energized the armature *d'* becomes locked so that the passage of 80 the car over the switch 77 does not affect the operation of restoring the signal.

The signal system herein shown is adapted to be operated by a car passing in either direction. It will be noticed that both signal boxes are alike and that the track switches 77 and 80 at each end of the block are so arranged that in whichever direction the car is traveling the track switch 77 will be first 90 operated at the entering end of the block and the track switch 80 will be operated at the exit end of the block. At the turn-out between the blocks, there is a track switch 103 in the siding connecting with the signal 95 box at the end of the block from which the car has come, and a similar track switch 108 in the main line opposite the siding connecting with the signal box at the end of the block from which the car on the main line 100 has just emerged, so that in whichever direction a car is passing the signals in the block from which the car has just come will be restored.

It is not essential to my invention that the 105 circuit connections should be made by means of track switches as trolley switches might be readily substituted for the track switches. Where track switches are employed instead of trolley switches, however, it is desirable 110 to have the two direction-controlling magnets *d* and *e* which are for the purpose of controlling the direction of the current according to the direction in which the car is passing, that is, whether passing into or out 115 from the block. A trolley switch, however, is usually constructed so that within the switch itself is means for controlling the direction of the current according to the direction that the car is moving and where trolley switches are employed, it is not necessary to use these magnets *d* and *e* in the signal box. 120

Another feature of my invention to which I desire to call attention is the fact that the signals 90 and 71 are in signal-containing 125 circuits separate from the circuits connecting the two signal boxes. The advantage of this arrangement is that if by any accident the wires 4 and 5 should become crossed with other wires when the signal system is 130

- in its normal condition, as shown in Fig. 1, the signals will not be operated.
- While I have shown herein the preferred embodiment of my invention, yet it will be obvious that the system as a system might be operated by mechanism different from what is shown, that is to say, the particular arrangement of magnets and contacts in the signal boxes is not essential to the invention which resides broadly in making a signal system in which the wires connecting the signal boxes are in a closed loop disconnected both from the feed and from the ground and in operating the signal as herein described. It will be obvious, therefore, that many changes in the constructional details of the parts may be made without in any way departing from the invention expressed in the appended claims.
- Having fully described my invention, what I claim as new and desire to secure by Letters Patent is:—
1. A block signal system comprising a normally-closed circuit extending the length of the block and disconnected from the source of electricity and from the ground, and means to establish a signaling circuit by opening said normally-closed circuit and connecting one point thereof to the source of electricity and another point thereof to the ground.
  2. A block signal system comprising a normally-closed circuit extending the length of the block and normally disconnected from both the source of electricity and from the ground, and means operated by a car entering the block to open said normally-closed circuit and connect one end thereof to the source of electricity and the other end thereof to the ground.
  3. A block signal system comprising a normally-closed loop extending the length of the block and disconnected both from the source of electricity and from the ground, means operated by a car entering the block to open said loop and connect it at the entering end of the block with a source of electricity and at the opposite end of the block with the ground.
  4. A block signal system comprising a normally-closed loop extending the length of the block and disconnected both from the source of electricity and from the ground, and means operated by a car entering either end of the block to open said loop and connect it at the entering end of the block with a source of electricity and at the opposite end of the block with the ground.
  5. In a signal system, the combination with a normally-closed loop extending the length of the block, a signal-containing circuit at each end of the block normally disconnected from the loop, and means to open the loop and connect said signal-containing circuits thereto.
  6. In a block signal system, the combination with a normally-closed loop extending the length of the block, means operated by a car entering the block to open said loop and connect it at the entering end of the block both to a source of electricity and to a signal, and to connect it at the opposite end of the block both to the ground and to a signal.
  7. In a block signal system, the combination with a normally-closed loop extending the length of the block and disconnected from both the source of electricity and the ground, of a signal-containing circuit at each end of the block, each being disconnected from said loop and one being connected to the source of electricity and the other to the ground, and means to break the loop and connect it to said signal-containing circuits.
  8. In a block signal system, the combination with a normally-closed loop extending the length of the block and disconnected from both the source of electricity and the ground, of a signal-containing circuit at each end of the block, each being disconnected from said loop and one being connected to the source of electricity and the other to the ground, and means operated by a car entering the block to break the loop and connect it to both of the signal-containing circuits.
  9. In a block signal system, the combination with a normally-closed loop extending the length of the block and disconnected from both the source of electricity and the ground, of a signal-containing circuit at each end of the block, each being disconnected from said loop and one being connected to the source of electricity and the other to the ground, means operated by a car entering the block to break the loop and connect it to both the signal-containing circuits, and means operated by a car leaving the block to restore the loop and disconnect it from the signal-containing circuits.
  10. In a block signal system, the combination with a closed loop extending the length of the block, of two signal-containing circuits at each end of the block, one circuit at each end being connected to the source of electricity and at the other end to the ground and all of said circuits being disconnected from the loop, and means actuated by a car entering the block from either end to open the loop and connect it at said end to one of the signal-containing circuits and at the other end to an oppositely-disposed signal-containing circuit.
  11. In a block signal system, the combination with a closed loop extending the length of the block, of two signal-containing circuits at each end of the block, one circuit at each end being connected to the source of electricity and at the other end to the ground and all of said circuits being disconnected from the loop, and means actuated by a car

entering the block to open the loop and connect it at the entering end of the block with the signal-containing circuit connected with the source of electricity and at the opposite 5 end of the block with the signal-containing circuit connected to the ground.

12. In a block signal system, the combination with a closed loop extending the length of the block, of two signal-containing circuits at each end of the block, one circuit at 10 each end being connected to the source of electricity and at the other end to the ground and all of said circuits being disconnected from the loop, means actuated by a car entering the block to open the loop and connect it at the entering end of the block with the signal-containing circuit connected with the source of electricity and at the opposite end of the block with the signal-containing 15 circuit connected to the ground, and means actuated by a car leaving the block to restore the loop and disconnect the signal-containing circuits therefrom.

13. In a block signal system, the combination with a closed loop extending the length of the block and disconnected from the source of electricity and from the ground, means to open said loop and connect it at one end of the block to the source of electricity and at the same time connect it to the ground first at the same end of the block and then at the opposite end thereof.

14. In a block signal system, the combination with a signal wire and a signal-restoring wire extending the length of the block and normally connected at their ends to constitute a closed loop, of means operated by a car entering the block to open said loop at both ends and connect one end of the signal 40 wire to the feed and the other end to the ground.

15. In a block signal system, the combination with a signal wire and a signal-restoring wire extending the length of the block

and normally electrically connected at each 45 end, of a signal-containing circuit at one end of the block normally disconnected from the signal wire, and means operated by a car entering the opposite end of the block to break the connection between said two 50 wires at both ends of the block and connect the signal wire with the signal circuit and also with the feed and ground.

16. In a block signal system, the combination with a signal wire and a signal-restoring wire extending the length of the block and normally electrically connected at each 55 end, of a signal-containing circuit at one end of the block normally connected with the ground and disconnected from the signal wire, of means operated by a car entering the opposite end of the block to break the connection between the two wires at both 60 ends of the block and to connect the signal wire at the entering end of the block with the feed and at the opposite end with the signal-containing circuit.

17. In a block signal system, the combination with a signal wire and a signal-restoring wire extending the length of the block, 70 of a signal-containing circuit at one end of the block normally connected with the ground and disconnected from the signal wire, means operated by a car entering the opposite end of the block to connect the signal wire at said end of the block with said feed and at the first-named end of the block with the signal-containing circuit, and means operated by a car leaving the block to establish a circuit through the signal-restoring wire thereby to restore the signal.

In testimony whereof, I have signed my name to this specification, in the presence of two subscribing witnesses.

JOHN J. RUDDICK.

Witnesses:

LOUIS C. SMITH,
FREDERICK S. GREENLEAF.
